UNITED STATES PATENT OFFICE.

HENRY P. CLAUSEN, OF MOUNT VERNON, AND CHARLES L. GOODRUM, OF NEW YORK,
N. Y., ASSIGNORS TO WESTERN ELECTRIC COMPANY, INCORPORATED, OF NEW
YORK, N. Y., A CORPORATION OF NEW YORK.

TELEPHONE-EXCHANGE SYSTEM.

1,371,737.

Specification of Letters Patent. Patented Mar. 15, 1921.

Application filed July 11, 1919. Serial No. 310,059.

To all whom it may concern:

Be it known that we, HENRY P. CLAUSEN and CHARLES L. GOODRUM, citizens of the United States, residing at Mount Vernon, in the county of Westchester and State of New York, and at New York, in the county of New York and State of New York, respectively, have invented certain new and useful Improvements in Telephone-Exchange Systems, of which the following is a full, clear, concise, and exact description.

This invention relates to improvements in telephone exchange systems and has particular reference to means for operating the switches therefor.

In automatic systems, the most commonly employed method of operating switches has been by direct current impulses transmitted over portions of a line, other portions of which are opaque to such impulses by reason of the use of condensers or other existing conditions.

An object of this invention is to employ alternating current for operating a switch to select telephone lines and also to control the release of said switch.

A feature of the invention is to connect to a line an alternating current generator of a frequency sufficiently low to be inaudible in a telephone receiver and operate said generator, when the line is taken, to transmit an alternating current thereover which will actuate an electromagnetic device to control the release of a switch.

Another feature is the provision of a second alternating current generator of a higher frequency which may or may not be audible in a telephone receiver and which, when connected to a line in response to interruptions therein, will control the operation of a switch in the usual manner.

The inventive idea involved is capable of receiving a variety of expressions, some of which, for the purpose of illustrating the invention, are shown in the accompanying drawing; but it is to be expressly understood that said drawing is employed merely for the purpose of facilitating the description of the invention as a whole, and not to define the limits thereof, reference being had to the appended claims for this purpose.

In the drawing, Figure 1 is a diagrammatic view of a circuit arrangement show-

ing the application of the invention to a metallic circuit. Fig. 2 is a similar view illustrating the application of the invention to a phantom circuit, only so much of the invention being shown as is necessary for an understanding thereof.

The invention permits of the operation of switches over a circuit containing condensers or various conditions which render the circuit opaque to direct current.

It is believed that the invention will be fully understood from the following detailed description of the operation.

When a subscriber at substation 1 initiates a call by removing his receiver from its switchhook, a line or finder switch will be operated, in a manner well known in the art, to connect the calling trunk line to an idle trunk. Line relay 2 will be energized over a circuit extending from grounded battery, right winding of said relay, winding 3 of a repeating coil, wiper of the line or finder switch, substation apparatus 1, the other wiper of the line or finder switch winding 4 of said repeating coil and left winding of relay 2 to ground. In energizing, relay 2 establishes a circuit for slow-to-release relay 5 extending from ground through the front contact and outermost armature of relay 2 and winding of relay 5 to grounded battery. This relay, in attracting its right armature, connects a low frequency current generator 6 to the sides 7 and 8 of the trunk. This alternating current will pass through the condensers 9 and 10 and winding of relay 11 to energize the same. Energization of relay 11 operates to seize a selector switch 13 having primary and secondary stepping movements. By attracting its right armature relay 11 closes a circuit for relay 12 of selector switch 13, which circuit extends from grounded battery, through right winding of relay 12, back contact and upper armature of cutoff relay 14, winding 15 of a repeating coil, back contact and armature of relay 16, right armature and front contact of relay 11, winding 17 of said repeating coil, inner lower armature and back contact of relay 14 and left winding of relay 12 to ground. Relay 12 attracts its armature and establishes a circuit for slow-to-release relay 18.

When relay 11 attracts its left armature, a

busy test will be provided for switch 13 over a circuit extending from ground at the left armature of relay 11, conductor 19, off-normal switch 28 when the same is closed 5 upon the first step of the switch, back contact and outer armature of magnet 27 to brush 25. It will be noted that when relay 2 is energized, by attracting its middle and innermost armatures, it disconnects a high 10 frequency current generator 20 from the telephone line.

Switch 13 is now in condition to receive 15 impulses transmitted from substation 1 and in response to each of these impulses, line relay 2 is deenergized and connects the high frequency generator 20 to the sides 7 and 8 of the line. Current from this generator 20 passes through condensers 9 and 10 and the winding of relay 16 which is tuned to respond only to high frequency currents in any manner well known in the art. Upon 25 each application of the high frequency alternating current to the line in response to the interruptions of line relay 2, relay 16 is energized thus interrupting the circuit for line relay 12 which, in releasing its armature, establishes a circuit for the primary stepping magnet 21 of switch 13 extending from grounded battery, through the winding of said magnet, winding of the slow-to-release relay 22, front contact and armature of relay 18, lowermost armature and back contact of relay 14, back contact and armature of relay 12 to ground. Relay 22 30 becomes energized in this circuit and, together with relay 18, maintains its armature attracted throughout the transmission of impulses. Magnet 21 operates to step brushes 23, 24 and 25 of switch 13 in a 35 group selecting movement. When relay 22 is energized, a circuit is established for test relay 26 extending from grounded battery, winding of said relay and armature and front contact of relay 22 to ground. Relay 40 26 locks up over a circuit from grounded battery through its winding, front contact and armature, outer armature and back contact of secondary stepping magnet 27, off-normal contact 28 which is closed upon 45 the first primary step of the switch, conductor 19, and left-hand armature and front contact of relay 11 to ground. At the termination of the series of impulses, line relay 2 maintains its armatures attracted and thus 50 55 permanently disconnects the generator 20 from the line with the result that stepping relay 16 will remain deenergized to maintain closed the previously described circuit for the line relay 12. This relay also maintains its armature attracted and opens the 60 circuit through the slow-to-release relay 22 which, after an interval, releases.

A self-interrupting circuit is then established for the secondary stepping magnet 27 65 extending from grounded battery, winding,

inner armature and back contact of said magnet, back contact and armature of relay 22, front contact and armature of relay 26, outer armature and back contact of magnet 27, off-normal contact 28, conductor 19 70 and left-hand armature and front contact of relay 11 to ground. Magnet 27 now operates to step brushes of switch 13 over the terminals of the selected group to hunt for an idle trunk therein. The busy condition 75 of trunks in this group of terminals is denoted by ground upon test terminal 29 and when brush 25 engages the terminal of a busy trunk, the locking circuit for test relay 26 will be maintained through brush 25 and 80 terminal 29 of said trunk to ground. Magnet 27 will therefore continue to step the brushes of the switch over terminals of busy trunks until an idle one is reached. At this time, brush 25, no longer finding ground, 85 opens a locking circuit for relay 26 and thus permanently breaks the circuit of stepping magnet 27 whereupon the brushes of the switch will come to rest upon the terminals of the idle trunk. When relay 26 releases, a 90 circuit is established for cut-off relay 14 extending from grounded battery, winding of said relay, back contact and armature of relay 26, outer armature and back contact of magnet 27, off-normal contact 28, conductor 19 and left-hand armature and front contact of relay 11, to ground. This circuit is maintained until the deenergization of relay 11 caused by the retraction of the right-hand armature of relay 5. By attracting its 95 armatures, relay 14 extends the calling line to the next succeeding switch which may be operated in the same manner as described in connection with switch 13. Relay 14 also permanently opens the circuit for relay 100 105 12 which, in releasing, causes the deenergization of slow-to-release relay 18.

At the termination of the conversation between a calling and a called subscriber, release of the switch 13 is controlled by the 110 calling subscriber. When the receiver is replaced upon its switchhook at substation 1, line relay 2 deenergizes and opens the circuit for slow-to-release relay 5. This relay then, in turn, releases its armature to disconnect the low frequency current generator from the telephone line and thus cause the release of relay 11. By retracting its left armature, this relay opens the holding circuit of relay 14, which then releases. A circuit is then established for release magnet 30 extending from grounded battery, winding of said magnet, spring 31 of off-normal contact 28, back contact and armature of relay 18, lowermost armature and 115 back contact of relay 14, back contact and armature of relay 12 to ground. Magnet 30 operates to restore the brushes of the switch to normal position whereupon off-normal contact 28 is also restored and the ener- 120 125 130

gizing circuit of magnet 30 permanently opened. The switch is now in position for another operation.

In Fig. 2, the invention is shown as applied to a phantom circuit and it is believed that a brief reference to the disclosure in this figure will enable those skilled in the art to understand the invention when considered in connection with the foregoing 10 description.

In this figure, 6' indicates the low frequency alternating current generator which is connected to the line when slow-to-release relay 5' is energized in response to the operation of the line relay 2'. The connection of the generator 6' to the line causes the energization of relay 11', the operation of which is precisely the same as that of relay 11. In response to interruptions in the line 20 circuit caused by impulses transmitted, relay 2' deenergizes to connect the high frequency alternating current generator 20' to the line whereby stepping relay 16' is operated to control the stepping of a switch 25 (not shown) similar to switch 13.

What is claimed is:

1. In a telephone system, an automatic switch, means for operating said switch, a release control magnet and alternating current means for maintaining said magnet energized during the operation of said switch.

2. In a telephone system, an automatic switch, a release control magnet, one source of alternating current means for energizing said magnet to permit of the operation of said switch, and another source of alternating current means for causing the operation of said switch.

3. In a telephone system, a telephone line, an automatic switch, means actuated upon the seizure of said line for transmitting an alternating current thereover, release control means responsive to said current, and 45 alternating current controlled means for operating said switch.

4. In a telephone system, an automatic switch, means for operating said switch, means for controlling the release of said switch, and sources of alternating current 50 of different frequencies, one of which controls the operation of said operating means, and the other the operation of said releasing means.

5. In a telephone system, a telephone line, 55 an automatic switch, means actuated upon the seizure of said line for transmitting an alternating current thereover, means responsive to said current for controlling the release of said switch, means responsive to 60 impulses for transmitting another alternating current over said line, and means responsive to the last named alternating current for operating said switch.

6. In a telephone system, a telephone line, 65 an automatic switch, means actuated upon the seizure of said line for transmitting an alternating current thereover, a relay responsive to said current for controlling the release of said switch, a relay responsive 70 to impulses for transmitting another alternating current over said line, and means responsive to the last named alternating current for operating said switch.

7. In a telephone system, telephone lines, 75 an automatic switch, a relay for controlling the setting of said switch, a relay for controlling the release of said switch, sources of alternating current of different frequencies, means for extending a calling line to said 80 switch and for applying alternating current from one of said sources to said release relay to maintain the same operated, and manually controlled means for applying impulses of alternating current from 85 the other source of the first named relay for controlling the setting of said switch on one of said lines.

In witness whereof, we hereunto subscribe our names this 9th day of July, A. D. 1919. 90

HENRY P. CLAUSEN.
CHARLES L. GOODRUM.
